CLOSURE FOR RUBBER DRUMS

Kenneth F. Fay and Warren L. Odenwelder,
Easton, Pa., assignors, by mesne assignments, to
The Pennsylvania Salt Manufacturing Com-
pany, Philadelphia County, Pa., a corporation
of Pennsylvania

Application March 4, 1939, Serial No. 259,714

1 Claim. (Cl. 150—8)

This invention relates to closures for rubber drums such as are used, for example, in the handling of hydrofluoric and muriatic acids. Drums for this purpose are usually made of a soft flexible rubber and are often lined with a synthetic rubber capable of withstanding the corrosive action of the acids. The top walls of such drums are usually provided with integrally formed rubber necks through which the contents of the drums can be removed with the aid of rubber nozzles or siphon pipes. Due to the soft flexible qualities of the rubber material forming such necks and the nature of the materials carried by the drums, considerable difficulty has been encountered by the art in providing a closure for such drum necks which is inexpensive to make and can be applied readily to the drum neck and yet can be depended upon to maintain a liquid tight seal during the handling of the drum and will last as long as the drum itself. The closures that have heretofore been used extensively for this purpose were either rubber plugs provided with external threads adapted to threadedly engage internal screw threads provided in the inner walls of the rubber necks of the drums or metal closures consisting of an externally threaded annular or ring member mounted on the neck of the drum beneath an external flange provided on the outer end of such neck and a cap member adapted to be screwed on the annular member so that the flange of the neck was clamped therebetween. Both of these types of closure are too expensive for the purposes for which they were devised and in order to open and close such closures it is necessary to use a large clumsy wrench. A further disadvantage of these constructions is that their usefulness was short lived because of the corrosive action of the acids carried by such drums, the acid swelling the threads on both the neck and the stopper in the plug type of closure thereby not only destroying the usefulness of the stopper but also making it necessary to have the whole drum replaced, whereas in the second type of closure, the corrosive action of the acid on the metal would cause the threads of the cap to become stuck to the threads of the annular member so that the cap could not be unscrewed. Furthermore the cap type of closure heretofore in use had the tendency to pop off the rubber neck of the drum whenever the drum was dropped or bounced on the ground during handling.

It is the purpose of the present invention to provide an improved form of metal closure which is relatively inexpensive to make, can be at-

tached readily to the neck of a rubber drum and will in its attached condition not come off even during relatively rough handling of the drum and which will provide a liquid-tight seal having no metal parts coming into contact with the contents of the drum.

Other objects as well as the advantages of the closure of this invention will become more apparent after a perusal of the following description taken in connection with the accompanying drawing in which Fig. 1 is a side elevation showing the closure assembled on the neck of a rubber drum; Fig. 2 is a top plan view of the parts shown in Fig. 1; Fig. 3 is a vertical section taken along the line 3—3 of Fig. 2 and Fig. 4 is a top plan view similar to Fig. 2 with the closure cap removed.

In the drawing the neck of the drum is designated by the reference character 10 and, as is usual, is integrally formed with the top wall 11 of the drum which is only partially shown. The closure, including the neck 10 and the top wall 11, is made of a soft flexible rubber, the interior wall of which may be lined with a synthetic rubber capable of withstanding the corrosive action of the acids to be contained in such drum, such for example, as the synthetic rubber known as "Neoprene" manufactured by E. I. du Pont de Nemours and Company. The upper or outer end of the neck 10 is provided with an outwardly extending flange 12 to which is clamped the closure of this invention.

The closure comprises a collar or annular retaining member 13 which is mounted on the neck 35 of the drum beneath the flange 12 thereof and a cap member 14 which seats on the neck flange 12 and is secured to the annular retaining member 13 with the flange 12 disposed therebetween. The members 13 and 14 may be made of any kind of suitable material but it is preferred to make them of bronze so as to make them resistant to corrosion. The annular retaining member 13 has an outside diameter greater than the outside diameter of the flange 12 and an inside diameter at the circumferential line which forms the juncture between the upper surface 15 thereof and the interior wall 16 thereof approximately the same as the exterior diameter of the neck 10 so that the exterior surfaces of the neck 10 are snugly engaged by the retaining member 13 along such line of juncture. The interior wall 16 of the member 13 tapers outwardly from the upper surface 15 of such member so at the circumferential line which forms the juncture between such wall and the under surface 17 of the

member, the inside diameter of the retaining member 13 is only slightly smaller than the outside diameter of the flange 12. In the construction illustrated, the frusto-conically shaped interior wall 16 of the annular member 13 has a taper of approximately fifteen degrees with the vertical. An advantage of constructing the retaining member 13 in this form is that it makes it possible to slip the member over the flange 12 of the neck, the tapered inner wall 16 of such member facilitating this operation as will be readily apparent. By forming the member 13 so that it provides a snug fit at the junction of the lower surface of the flange 12 with the exterior wall of the neck 10, the flange is prevented from slipping through such member and will retain the same on the neck 10 through even the roughest handling of the rubber drum.

The retaining member 13 is provided with two outwardly extending lugs or ears 18, 18 which are each provided with an angularly shaped opening 19, preferably square, adapted to receive snugly the angular shank portion of a carriage bolt 20. The threaded stems of the bolts 20 extend up through aligned circular openings provided in the outwardly extending lugs or ears 21 of the cap member 14 and have screwed on their upper ends the nuts 22.

The cap member 14 which has an outside diameter greater than that of the flange 12 and substantially equal to the outside diameter of the retaining member 13, is provided with a recess 23 in its under surface which is circular in form and has a diameter only slightly greater than the outside diameter of the flange 12 so that the latter may be readily inserted therein. Cemented to the inner wall of the recess 23 is a rubber gasket 24 which is preferably composed of a synthetic rubber material, such as "Neoprene" and which prevents the contents of the drum from coming into contact with the metallic material of which the closure members 13 and 14 are formed.

From the foregoing, it will be evident that by reason of the tapered inner wall 16 of the retaining member 13, such member can be readily assembled on the neck of the drum even though the smallest diameter of such tapered wall is materially less than the outside diameter of the flange 12 and that when the cap member 14 is properly positioned in place with the flange 12 in the recess 23 and the nuts 22 tightened, such flange will be compressed between the upper surface 15 of the retaining member 13 and the interior sur-

faces of the recess 23 to provide a liquid-tight seal between the neck of the drum and the rubber gasket 24. By forming the retaining member 13 so that a snug fit is provided at the line of juncture of the flange and the neck, the closure assembly will be securely anchored so that it can not pop off even when the drum is dropped appreciable distances for example, four feet. The effectiveness of the anchorage can be further enhanced by providing an annular groove 25 on the top surface 18 of the retaining member 13 so that when the upper or cap member 14 is secured in position on the drum, a portion of the rubber material of which the flange 12 is constituted will be forced into the groove. Removal of the cap member 14 is readily accomplished by unloosening the nuts 22 on the bolts 20, the angularly shaped openings 19 in the lugs or ears 18 preventing the bolts from turning during this operation. As the distance between the undersurface of the retaining member 13 and the top wall 11 of the drum is appreciably smaller than the length of the bolts 20 even in the assembled condition of the closure, the bolts will not fall out or become lost during the period that the cap member is removed.

We claim:

In a closure for a receptacle and in combination, a receptacle neck made of resilient rubber or the like and provided at its outer end with an annular, outwardly extending flange, a rigid, unitary, annular retaining member positioned on the neck beneath the flange thereof, said retaining member having an upper wall in engagement with substantially the entire area of the undersurface of the flange and having an inner wall which tapers outwardly from said upper face of such member, the diameter of the member at the upper end of the inner wall thereof being approximately the same as the exterior diameter of the neck of the receptacle and the diameter of the member at the lower end of the inner wall thereof being approximately the same as that of the outside diameter of said flange, a cap member having a shallow recess in its under surface adapted to receive the flange of the receptacle neck, a gasket in the bottom of the shallow recess in the cap member for closing the opening in such neck, and means for securing said retaining and cap members together to clamp the flange of the neck therebetween.
